UNITED STATES PATENT OFFICE.

FRANK BENAJAH LONG AND EDWARD ARTHUR TAPPE, OF LOS ANGELES, CALIFORNIA.

PNEUMATIC ACTION FOR SELF-PLAYERS.

No. 895,382.

Specification of Letters Patent.

Patented Aug. 4, 1908.

Application filed March 23, 1907. Serial No. 364,101.

To all whom it may concern:

Be it known that we, FRANK BENAJAH LONG and EDWARD ARTHUR TAPPE, citizens of the United States, and residents of Los Angeles, in the county of Los Angeles and State of California, have invented a new and Improved Pneumatic Action for Self-Players, of which the following is a full, clear, and exact description.

10 The invention relates to cabinet players, self-playing pianos and like self-players, and its object is to provide a new and improved pneumatic action, arranged to insure long life, especially as to the pneumatics, and to 15 produce a quick and accurate response of the keys or strikers, according to the pneumatic to be produced.

The invention consists of novel features and parts and combinations of the same, 20 which will be more fully described herein- after and then pointed out in the claims.

A practical embodiment of the invention is represented in the accompanying drawings forming a part of this specification, in 25 which similar characters of reference indicate corresponding parts in all the views.

Figure 1 is a transverse section of the improvement as applied to a self-playing piano; Fig. 2 is an enlarged sectional side elevation 30 of one of the pneumatics; Fig. 3 is a trans- verse section of a modified form of the improvement; and Fig. 4 is an inverted plan view of the same, the bottom of the wind chest being removed along the line 4—4 of 35 Fig. 3.

The suction chamber A of the pneumatic action is connected by a tube B with a bellows C or other means of producing a suction action in the suction chamber A. 40 Into the latter opens one face of the dia- phragm D for a diaphragm chamber D' connected by the tube E with a corresponding aperture in the tracker board of the instru- 45 ment, and the said diaphragm D engages one end of a lever F extending within the suction chamber A and on the other end of this lever is secured, by a regulating screw, the stem G' of a valve G, normally seated on a port a opening into the suction chamber A, 50 and adapted to connect the latter with the channel b opening into the pneumatic H. The channel b is connected by a port c with the channel d leading to the atmosphere, and the said port c is adapted to be closed 55 by the valve G, to disconnect the channel b from the atmosphere and to connect the said

channel b by way of the port a with the suc- tion chamber A, to collapse the pneumatic H, as hereinafter more fully described.

The movable member H' of the pneumatic H is connected by a rod I with one end of a lever J, fulcrumed at its other end at J', and provided with an arm J² adapted to engage a keeper or bracket K' secured to the under side of the key or striker K, fulcrumed in the usual manner on the key board L of the instrument. An adjusting screw J³ on the lever J engages the arm J², for adjusting the latter, so as to bring the free end thereof into proper relation with the keeper K', arranged on the forward end of the key, as indicated in Fig. 1. As the free end of the arm J² engages the top of the keeper K' it is evident that the key K can be played by hand without interfering with the arm J², the lever J and the parts connected therewith; but when the pneumatic H is collapsed and a downward swinging motion is given to the lever J, then the arm J² carries the keeper K' and consequently the key along so as to actuate the key and consequently the piano or other instrument. The pneumatic H is provided with a fixed member H² which is approximately parallel to the movable member H', previously mentioned, and the said mem- 85 bers H' and H² are connected with each other by the flexible tubular connection H³ of rubber, leather or a like material. The edge of the movable member H' is provided with a guide H⁴ of felt, leather or other suit- 90 able material and fitting the inner surface of a casing H⁵ inclosing the pneumatic H and forming a guide for the movable member H'. Now when the instrument is used and an 95 aperture of the note sheet registers with an aperture in the tracker board and air passes by way of the tube E into the diaphragm chamber D', then the diaphragm D thereof moves outward into the suction chamber A and consequently imparts a swinging motion 100 to the lever F which lifts the valve G off the port a, to open the latter and move the valve G onto the port c to close the latter. When 105 this takes place air is drawn from the pneumatic H by way of the channel b and port a and the suction chamber A, so that the pneumatic H collapses, that is, the movable member H' moves parallel downward towards the fixed member H², and in doing so the mov- 110 able member pulls the rod I downward with it for the rod I to impart a downward swinging motion to the lever J, to actuate the corre-

sponding key for sounding the proper string of the piano. As soon as the note sheet aperture has passed the tracker board aperture and the latter is closed by the note sheet then the diaphragm D returns to its normal position, to allow the valve G to drop and close the port a and open the port c, whereby the pneumatic H is disconnected from the suction chamber A and is connected 10 with the atmosphere, to allow the air to pass into the pneumatic H to inflate the same. When this takes place the movable member H' moves back to its uppermost position, and in doing so it returns the lever J and allows the key K to move back to its normal position of rest.

As illustrated in Fig. 1, the lever F is in the form of a bell crank lever, and as shown in Figs. 3 and 4 the lever F' for connecting 20 the diaphragm D with the valve G is a straight lever, but otherwise the construction shown in Figs. 3 and 4 is approximately the same as the one above mentioned in reference to Figs. 1 and 2, so that further description of the same is not deemed necessary. Now by constructing the pneumatic H in the manner described, the movable member H' moves parallel towards and from the fixed member H², and as the flexible connection 25 H³ has no pre-arranged creases or folds it is not liable to be readily injured, and consequently long life of the pneumatic is insured. It will also be noticed that by making the pneumatic in the manner described it can be 30 made of suitable capacity without occupying much space.

The entire pneumatic action shown and

described is very simple, durable and compact in construction, and is not liable to easily get out of order as it is composed of 40 comparatively few parts.

Having thus described our invention, we claim as new and desire to secure by Letters Patent:

1. A pneumatic action provided with a 45 pneumatic, having a fixed member, a movable member approximately parallel to the said fixed member, a flexible connection between the said fixed and movable members, to allow the movable member to move approximately parallel to and from the said fixed member, an exterior guide for the edge of the said movable member, and a casing 50 inclosing the said pneumatic and engaged at its inner surface by the said guide, to guide 55 the movable member in its movement.

2. A pneumatic action provided with a pneumatic having a fixed member, a movable member approximately parallel to the said fixed member, a flexible connection between the said fixed and movable members, and a casing inclosing the pneumatic and engaged at its inner surface by the edge of the 60 movable member to guide said movable member in its movement.

In testimony whereof we have signed our names to this specification in the presence of two subscribing witnesses.

FRANK BENAJAH LONG.
EDWARD ARTHUR TAPPE.
